ATTORNEY.

UNITED STATES PATENT OFFICE.

JOSEPH A. GARDNER, OF MEMPHIS, TENNESSEE.

ARTIFICIAL-TOOTH STRUCTURE.

Application filed February 29, 1924. Serial No. 695,929.

To all whom it may concern:

Be it known that I, JOSEPH A. GARDNER, a citizen of the United States, residing at Memphis, county of Shelby, and State of Tennessee, have invented certain new and useful Improvements in Artificial-Tooth Structures, of which the following is a full, clear, and exact description, such as will enable anyone skilled in the art to make and use the same.

My invention relates to porcelain tooth crowns and interlocking backings or support therefor and especially to that particular class of tooth crowns which are to be built up and either singly or in connection with other crowns or dummies are to be built into a bridge which is to be supported by attachment to adjacent teeth. In this class of dental work porcelain fronts or facings of various sizes and shapes and of an extensive range of shades of white are used. The exact shade of these facings cannot be determined before burning and it is necessary that they be pre-formed and burned in order that proper selection can be made. These facings are carefully selected to as nearly as possible match the shades of the adjacent teeth with which they are to be used and are selected of the proper size and type to properly replace the missing teeth. It is then necessary to make a backing on which these fronts may be properly aligned and spaced and by which they may be attached to and supported by adjacent sound teeth. It is also desirable if this work is to be done in a first class manner to build up the root end of these facings and over the root end of the backing so that a smooth ridge-lap or a smooth and polished root end which conforms exactly to the shape of the cavity in the gum left by the removal of the tooth, is formed. In doing this work, it becomes necessary to attach the tooth facing to the backing and detach it from the same a number of times during the progress of the work. First, it is necessary to attach these together in order that a proper ridge-lap, or a root member may be built up. It is then necessary to detach the backing in order that this lap or this root member which is preferably of porcelain, may be properly baked to fuse or vitrify it to the facing without damage to the backing or without damaging the facing by reason of the unequal expansion of the backing and the facing. It is then necessary to attach the back-

ing to the facing in order to properly align and space the facing or facings with reference to the adjacent teeth or to themselves or both and this having been done it is necessary to remove these facings in order that the backing may be properly united into a single unit, a process which if carried out, with the facings attached would result in the cracking of the facings because of the expansion of the backing, and finally when the individual tooth structures have been built and the backing completed, it is necessary to assemble and join each tooth facing at and to its proper place on the backing.

While this outlines the steps necessary in the work, it is ordinarily necessary to attach each facing to, and remove the same from, the backing and to attach each facing and root to, and remove the same from, the backing quite a number of times instead of the limited number mentioned above.

The object of my invention is to make a tooth facing and backing therefor which may be readily attached to or detached from each other both before and after the root has been built on. I carry out this object as will be more fully hereinafter set out in the drawings, specification and claims.

In the drawings, which are on a scale much larger than the true size;

Fig. 1 is a reverse view of a tooth facing with the corresponding backing therefor shown detached; one-half of the backing having been cut away to more clearly show the locking member which engages the tooth facing.

Fig. 2 is a similar view showing two locking members instead of one.

Fig. 3 is a horizontal section through one of the backing plates, on the line III—III of Fig. 4.

Fig. 4 is a front view of the backing plate, and

Fig. 5 a side view of the same. The plate having two locking members.

Figs. 6, 7 and 8 are similar views of a plate having a slightly different form of locking member, Fig. 5 showing the plate and locking member engaged with the tooth facing.

Fig. 9 shows a vertical section through a tooth facing with a portion of the root end of the facing ground away to permit building on the root section and with the backing plate in place.

Fig. 10 is a similar section showing the

root structure built in place and the backing member still interlocked.

Fig. 11 is a similar section showing the backing section ready to be replaced after 5 the root section has been baked on.

Fig. 12 is a side elevation showing the root section completed and the backing plate again inserted and built up.

Fig. 13 is a vertical section through a tooth 10 facing showing a locking member without backing plate engaged with the groove in the back of the tooth facing.

Referring now to the drawings in which the various parts are indicated by numerals. 15 1 is the tooth facing which ordinarily is approximately one-half the thickness of a tooth. 2 is the occlusal end, and 3 the root end, the front 4 of this facing being of the shape of the front of the desired tooth. The 20 back of the facing 5 is preferably a flat surface in which is formed a groove 6 having undercut sides, this groove ordinarily opening into the root end 3 but not extending through to the occlusal end 2. At the occlusal end of this groove the sides of the undercut groove 6 are cut away and a straight sided opening 7 formed thereinto. The backing plate 8 is a thin plate ordinarily of gold or platinum which plate has a 25 projecting member 9 adapted to slide in the groove 6 and hold the plate firmly against the back 5 of the tooth. This member 9 may be inserted in the open end of the groove 6, or it may be inserted in the groove 30 through the enlarged opening 7, and then shifted longitudinally to secure the plate to the tooth facing.

In Fig. 3 the tooth facing is identical in 40 every respect except that it has been provided with two openings 7^A, 7^B into which members 9^A, 9^B projecting from the plate 8^A may be inserted. With this form of tooth facing the plate 8 with a single member 9 may be used or the plate 8^A with the double 45 members 9^A, 9^B as may be desired, or even members 9^C (Fig. 13) without pre-attached backing plate.

In Figs. 3, 4 and 5 I show the plate 8^A with the members 9^A, 9^B projecting therefrom.

In Fig. 9 I show a section of the tooth facing 1 with the root end 3 thereof ground off to permit building up the root structure thereon. At this stage of the work, the 55 plate 8 may be inserted into the groove 6 from either end; that is, it may be put in at the root end and pulled into the slot or it may be slipped in through the opening 7 and shifted to place. When however, as 60 shown in Fig. 10, the root structure 3^A has been built in place on the root end of the facing 1, the former open end of the slot 6 in the root end of the tooth facing is closed and it would therefore be impossible 65 to remove the backing plate therefrom were

the opening 7 not provided. When this root structure has been built on, it is as before stated, necessary to remove the plate 8 in order that the root structure may be baked and vitrified or fused to the root end 3 of 70 the tooth facing. Should the backing plate 8 be left in place while this baking is being accomplished, the expansion of the gold would be such as to crack the porcelain structure of the facing, and in many cases, 75 the heat necessary to vitrify the porcelain would be sufficient to soften and distort or even melt the gold backing plate even should the expansion not cause trouble. It will therefor be seen that it is necessary 80 that the plate be removed, and a number of makeshift efforts have previously been made to accomplish this result.

After baking the porcelain, the backing plates can also be easily replaced for the purpose of assembling the teeth and shaping up the bridge ready for completion and after this assembly has been made, the tooth facings may be readily removed to complete 85 the bridge structure, and thereafter be as 90 readily replaced and finally cemented thereto to complete the assembly.

It is also possible as indicated in Fig. 13, to use a locking member 9^C which is not pre-attached to a backing. In such case the 95 locking member is placed in proper position in the groove 6 of the tooth facing as shown and a wax backing 10 is shaped thereover. Thereafter the wax backing with the locking member 9^C attached is withdrawn, an investment mold made, and a casting made in 100 the usual manner with the locking member secured to the backing.

It will be especially noted that the shape of the locking member is not material so 105 long as it may be inserted through the opening into the groove and when shifted, engages the sides of the groove to hold the backing plate against the backing, and the means for securing the locking member to 110 the plate is also not material so long as it be secured firmly thereto.

It will also be noted that the groove is not necessarily open at the root end of the facing though shown that way.

Having now fully described my invention, what I claim and desire to secure by Letters Patent of the United States, is:—

1. A tooth facing approximately one-half tooth thickness, having a groove with undercut sides in the back thereof, said groove being open at the root end of said facing and extending toward, but not to the occlusal edge of said facing, and having a portion of the said sides cut away whereby openings 120 are provided into both ends of said groove.

2. A tooth facing having a groove with undercut sides in the back thereof, said groove being open at the root end of said facing and extending toward, but not to the 125 130

occlusal edge of said facing and having a portion of the said sides cut away whereby openings are provided into both ends of the said groove.

5 3. A tooth facing having a groove with undercut sides in the back thereof, said groove extending the major portion of the length of said facing and having portions, minor in length, of the sides of said groove 10 cut away to provide openings thereinto.

4. A tooth facing having in the back thereof a longitudinal groove with undercut sides extending from a point near the occlusal end of said facing toward the root end thereof, 15 and having a portion of the sides of the said groove cut away to provide an opening into the said groove, which opening is of minor length as compared with the total length of the groove.

20 5. A tooth facing having in the back thereof a longitudinal groove with undercut sides, said groove being open at the root end of said facing and extending therefrom a major portion of the length of said facing, 25 and having a portion of the said sides cut away to provide an opening thereinto of minor length as compared with the length of the remaining portion of the groove.

6. The combination with a tooth facing, 30 having a longitudinal groove with undercut sides in the back thereof, said groove extending longitudinally a major portion of the length of said facing and having a minor portion of the length of said sides cut away 35 to provide an opening into the said groove of minor length as compared to the remaining length of the undercut groove; of a backing plate therefor provided with a forwardly extending member adapted to enter said 40 groove through the opening thereinto and to be longitudinally shifted to engage with the undercut sides of said groove at any portion of the entire length of the undercut section of said groove, whereby said plate may 45 be shifted to adjust its position longitudinally with reference to said tooth facing.

7. The combination with a tooth facing, 50 having a longitudinal groove with undercut sides in the back thereof, said groove being open at the root end of said facing and extending longitudinally a major portion of the length of said facing and having a minor portion of the length of said sides cut away near the occlusal end

of said groove to provide an opening into 55 the said groove of minor length as compared to the remaining length of the undercut groove; of a backing plate therefor provided with a forwardly extending member adapted to enter said groove through the opening thereinto or the open end thereof and to be longitudinally shifted to engage with the undercut sides of said groove at any portion of the entire length of the undercut section of said groove whereby said plate may 60 be shifted to adjust its position longitudinally with reference to said tooth facing, or may be removed from either end thereof.

8. The combination with a tooth facing 70 provided in the back thereof, with a longitudinal groove having undercut sides, said groove being open at the root end of said tooth and extending therefrom to a point near the occlusal end of said facing and having a minor portion of the sides of said groove cut away to provide an opening into the said groove at the occlusal end thereof; of a backing plate therefor, provided with a forwardly extending member adapted to enter said groove at either end thereof and to be shifted to engage with the undercut sides of said groove and hold said plate against the back of said facing at any portion of the length of the remaining undercut portion of 80 said groove.

9. The combination with a tooth facing provided in the back thereof with a longitudinal groove having undercut sides extending from a point intermediate the ends of 90 said tooth face toward the root end thereof and having portions of the sides of said groove cut away to provide openings into said groove, of minor length compared to the total length of said groove, of a backing 95 plate therefor provided with forwardly extending members adapted to enter said groove through the openings thereinto and to be longitudinally shifted to engage with the undercut sides of said groove and hold said plate against the back of said facing in 100 various positions of longitudinal adjustment.

In testimony whereof I have hereunto set my name.
